(57) **CLAIM**

The ornamental design for a roller ramp section for watercraft shore ramps, as shown and described.

DESCRIPTION

FIG. 1 is a perspective view of a roller ramp section for watercraft shore ramps with environment;

FIG. 2 is a close-up perspective view;

FIG. 3 is a front elevational view;

FIG. 4 is a rear elevational view;

FIG. 5 is a left side elevational view, the right side being the mirror image;

FIG. 6 is a top plan view; and,

FIG. 7 is a bottom plan view.

The broken lines in the drawings illustrate portions of the roller ramp section for watercraft shore ramps that form no part of the claimed design. The roller ramp is shown with a symbolic break in its length. The breakaway symbols and any portions of the roller ramp between the breakaway symbols do not form part of the claimed design.
